ATTORNEY

UNITED STATES PATENT OFFICE

165,952

WAITING ROOM SEAT OR SIMILAR ARTICLE

Raymond C. Weatherly, Dallas, Tex.

Application September 28, 1951, Serial No. 16,766

Term of patent 14 years

(Cl. D15—11)

To all whom it may concern:

Be it known that I, Raymond C. Weatherly, a citizen of the United States, residing at Dallas, Dallas County, Texas, have invented a new, original, and ornamental Design for a Waiting Room Seat or Similar Article, of which the following is a specification, reference being had to the accompanying drawing, forming a part hereof.

Figure 1 is a front perspective view of a waiting room seat or similar article, embodying my new design;

I claim:

The ornamental design for a waiting room seat or similar article, substantially as shown.

RAYMOND C. WEATHERLY.
